UNITED STATES PATENT OFFICE.

LUTHER L. SMITH, OF ANSONIA, CONNECTICUT.

APPARATUS FOR COATING WIRE.

SPECIFICATION forming part of Letters Patent No. 276,914, dated May 1, 1883.

Application filed February 7, 1883. (No model.)

To all whom it may concern:

Be it known that I, LUTHER L. SMITH, of Ansonia, in the county of New Haven and State of Connecticut, have invented a new Improvement in Apparatus for Coating Wire; and I do hereby declare the following, when taken in connection with accompanying drawings and the letters of reference marked thereon, to be a full, clear, and exact description of the same, and which said drawings constitute part of this specification, and represent, in—

Figure 1, a transverse section of the rack; Fig. 2, a longitudinal section; Fig. 3, a side view, showing the convolutions of wire standing between the teeth.

My invention relates to improvements in apparatus for coating wire invented by me, and for which Letters Patent were granted to me May 17, 1881, No. 241,742. In that invention, the essential feature of which consists in feeding the wire which is to be plated successively through the electrolytic solution in a helical path, the several convolutions of the coil being partially or wholly submerged in the electrolytic solution, and being made to rotate upon a horizontal axis, whereby the motion of the wire in passing through the solution is substantially like that of the thread of a screw which is being inserted into or drawn from a stationary object. In that apparatus I arranged wooden racks, the teeth of which project into the spaces between the convolutions of the wire which is to be plated, so as to separate or prevent the contact of the successive convolutions. The spaces between the convolutions are necessarily very narrow; hence the wooden teeth must be proportionately thin. In practice I have found that the movement of the wire between these teeth, in connection with the solution which they draw up to the wood, and which is absorbed by the wood, quickly destroys the wood teeth, so that they fail to perform their necessary office.

To overcome this difficulty is the object of my improvement; and it consists in a rack composed of a base with glass or equivalent non-conducting material teeth set in the base, as more fully hereinafter described.

A represents the base, which is made from wood or other suitable material, and in the upper surface of which is a groove, *a*, prefera-

bly of dovetail shape. Into this groove short pieces of glass, *b*, are set, the pieces corresponding in width substantially to the width of the groove, and between the successive pieces of glass a wood block, *d*, is placed in the groove, corresponding in shape to the dovetail shape of the groove, so that the block will be readily retained in its place to separate each glass tooth from the next, the thickness of the block being little greater than the diameter of the wire which is to ride between the teeth, as seen in Fig. 3. This rack or section of glass teeth extends the length of the bath, so that each convolution of wire throughout the bath stands in its own independent space between the teeth, and as the wire is advanced the convolutions pass between the teeth like a screw in its nut. By making the teeth of glass, perfect insulation is attained, and because of the separate and independent teeth thus produced any one may be readily removed when broken, or for other purposes, replaced, or a new tooth introduced, without interrupting the work, and thus being made of a hard material they do not absorb the moisture brought to them by the revolving wire; neither do they wear away by contact with the wire, as in the case of wood teeth.

What I claim as an improvement on my invention patented May 17, 1881, is—

1. In an apparatus for coating wire, the herein-described rack for separating the convolutions of wire, consisting of a base provided with glass or equivalent material teeth *b*, between which teeth the convolutions of the wire pass, substantially as described.

2. The base *A*, having a longitudinal groove in its surface, with glass or equivalent material teeth *b* set in said groove, with blocks *d* between successive teeth, substantially as described.

3. The base *A*, constructed with a longitudinal dovetail-shaped groove, teeth *b*, set in said groove, and blocks *d*, of dovetail shape, corresponding to the groove in the base and set between the successive teeth, substantially as described.

LUTHER L. SMITH.
